Attorneys

UNITED STATES PATENT OFFICE

JAMES B. PLATT, OF BALTIMORE, MARYLAND, ASSIGNOR TO STONE STRAW CORPORATION, OF WASHINGTON, DISTRICT OF COLUMBIA, A CORPORATION OF DELAWARE

CUT-OFF MECHANISM FOR TUBE MACHINES

Application filed April 22, 1931. Serial No. 532,091.

This invention relates to cut-off mechanism for tube machines, and it comprises a freely rotatable knife or cutter mounted for orbital movement about an axis in a horizontal plane and, simultaneously, for revolution about a vertical axis, gearing for causing bodily movement of the knife about such horizontal and vertical axes, whereby the knife will be projected periodically into the path of a tube 10 to be cut and, in approaching and receding from such path, will travel in the direction of movement of the tube, and guiding means for the tube for supporting it adjacent the point of cut; all as will be described hereinafter 15 and as claimed.

In the manufacture of paper tubes of small bore, particularly those known as artificial straws, it is common practice to form the tube on a mandrel and to feed it continuously from 20 the mandrel to a mechanism for cutting it into convenient lengths. Inasmuch as the formed tube is continuously in motion as it is fed from the forming mechanism to the cut-off, it is desirable to move the knife or 25 other cutter in the direction of movement of the tube at the same time it approaches and cuts through the tube, thereby to prevent buckling of the longitudinally moving tube by contact with a cutter operating in a fixed 30 plane.

Heretofore, the cutter has been rotated by gearing simultaneously with its movement into and out of engagement with the tube and its movement in the direction of tube travel, 35 after the manner shown in the prior patents to L. C. Maltby, Nos. 1,201,842 and 1,201,843, wherein a pinion is affixed to the knife to cause its rotation through drive gearing.

40 It has been found that the relatively slow rotation of a gear driven knife results in a speedy dulling of the blade to a point where imperfect cuts are made by it, this necessitating frequent shut-down of the machine for 45 replacement of cutters with attendant loss of time and productivity. Moreover, the speed at which a gear driven knife may be actuated is decidedly limited. A speed sufficiently high for efficient production is likely 50 to set up destructive forces which might not

only cause damage to the machine but which would imperil the operator.

I have found that it is possible to operate cut-off mechanisms at higher speeds than have heretofore been considered practicable 55 and at the same time to eliminate the defects and dangers attending the operation of prior art mechanisms at such high speeds. This has been accomplished by the present invention, wherein a freely rotatable knife or cutter is employed. An extremely high speed of rotation is imparted to it by a cutting operation in which it hits and passes through a paper tube into the path of which it is temporarily projected. The knife, in rotating at such 60 high speed not only effects a cleaner cut than a gear driven knife, but the blade does not readily lose its keenness and may be used for a considerably longer time than a gear driven 65 knife before its replacement becomes necessary.

70 My invention therefore has as its object to increase the efficiency and productivity of tube making machinery by providing a knife which is rotated at high speed by hitting the tube to be cut, thereby to effect a clean cut and to maintain the keenness of the cutting blade.

75 Other and further objects will be apparent from the following description and drawing, 80 in which

Figure 1 is a vertical sectional view of the cut-off mechanism comprising this invention,

Figure 2 is a top plan view of the mechanism, partly in section, 85

Figure 3 is a fragmentary view, partly in vertical section at right angles to the section of Figure 1,

Figure 4 is a detail view, partly in section, 90 of the knife mounting.

Referring more particularly to the drawing:

A fixed housing 10, having a removable cover 11, is formed with a downwardly extending boss 12 which is flanged for the reception of screws or bolts to fasten it to the bed of a machine (not shown), and which serves as a bearing for the vertical drive shaft 13. The upper end of shaft 13 is shoul- 100

dered for the support of a rotatable turret 14 to which it is pinned at 15, or is otherwise affixed. The turret comprises a base 16 and an upstanding annular wall 17, spaced from the fixed housing.

The annular wall of the turret preferably has spaced circumferential flanges extending outwardly adjacent its upper edge, and its interior is formed with integral ribs 18 upon the upper ends of which are seated bearing plates 19 and 20, held in position by screws 21 which are tapped into the ends of the ribs. As an additional support for the plates the interior wall of the turret may be machined to form an annular shoulder 22.

Another protuberance 23 is cast integrally with the wall 17 and is journalled to receive a vertical shaft 24 having a pinion 25 on its lower end (Figure 3) in mesh with an internally toothed gear 26 which is removably mounted in the fixed housing 10, as by screws 27. A bevel gear 28 is mounted on the upper end of shaft 24 and meshes with a bevel gear 29 on the cross shaft 30 which is received within a cut out portion of the plate 19 and is retained therein by a strap or bridge piece 31, the other end of the shaft being journalled in plate 20.

A crank 32, preferably of disk shape, is keyed to shaft 30 or fixedly mounted on it in any other well known manner, and the disk is radially slotted at 33 (Figure 4) for the reception of a stub shaft 34, one end of which is threaded for the reception of a nut 35 to hold it in position. A portion of the pintle 34 is of reduced diameter to define a shoulder against which a bearing cone 36 is seated. A second bearing cone 37 is slidably received on the pintle and is adjusted and retained thereon by a nut 38. An outer bearing race member 39 is revolvably and anti-frictionally supported on the pintle. It is shouldered at 40 and has a reduced threaded portion receiving a nut 41 which clamps the circular 45 knife 50 against the shoulder.

The turret 17 is slotted on opposite sides at 51 and 52 for free passage of the knife beyond the confines thereof in its travel within the fixed housing, and the housing is horizontally slotted at 53 so that a circular tube guide 54 may extend through its wall into the path of the knife 50. The guide has an annular groove 55 for tangentially receiving and supporting a tube to be cut, and is radially slotted at 56 for passage of the knife through the tube adjacent the point of its support.

The guide 54 is mounted on a shaft 57 which is journalled in a supporting member 58 provided with a depending skirt 59 which conceals a gear 60 on the lower end of shaft 57 and through which the guide is driven, the gear 60 being meshed with a ring gear 61 attached to the turret by screws 62 or in any other convenient manner.

The guide supporting member 58 is preferably attached to the housing 10 by screws 63, the housing having cast therewith a base 64 (Figure 2) for such attachment.

A vertical arm 65 rises from the base 64 and receives a tubular guide 66 which has a bell mouth 67 for receiving a tube from the forming mechanism and directing it into the annular groove in the circular guide 54.

In operation, as the shaft 13 and turret 17 are rotated the pinion 25 which is carried by the turret, and which is in mesh with the fixed internally toothed gear 26, will be rotated, thus driving the shaft 24, the rotation of which is transmitted through the meshed bevel gears 29 and 28 to cross shaft 30, thereby rotating the disk 32 which is mounted on that shaft. The knife is thereby bodily revolved about shaft 30 and, simultaneously, is revolved about the vertical axis of shaft 13. In the compound orbital travel of the knife about both horizontal and vertical axes it will be projected periodically into the path of a tube which is supported by the rotary guide and will cut through such tube by passing through the radial slot in the guide.

The knife being freely mounted on its pintle will be rotated by its impact against the tube in a cutting operation and a high speed of rotation will thus be imparted to it. The knife, in rotating at high speed, not only cuts the tube cleanly and with facility, but does not readily lose its keenness and may be used for long periods without replacement.

What I claim as my invention is:

1. Cut-off mechanism for tubes comprising a guide, a circular knife freely rotatable upon a supporting pintle, and mechanism for projecting the knife periodically into the path of the tube with a slashing stroke which will impart rotation to the knife.

2. In a cutting machine for tubes, the combination of a freely rotatable circular knife, means for revolving the knife bodily about an axis offset therefrom, and a rotary support for said means having an axis of rotation parallel with the plane of rotation of said knife.

3. The combination of two rotatable shafts, one driven by the other at an angle thereto, a freely rotatable cutter mounted for revolution about the axis of the driven shaft the plane of rotation of said cutter being coincident with that of its revolution, and means for rotating both said shafts.

4. Cut-off mechanism for tube machines comprising in combination, drive gearing, a freely rotatable knife actuated by said gearing and adapted to be projected outward at periodic intervals into the path of a tube to be cut thereby, a guide for said tube adapted to project it into the zone of cutting whereby contact of the knife against the tube in a cutting operation will impart a high speed of rotation to the knife.

5. A cut-off mechanism for tubes comprising a freely rotatable, circular knife mounted for orbital movement about a horizontal axis and, simultaneously, for revolution about a vertical axis, gearing for revolving the knife about such axes, and a guide for projecting a formed tube into the path of said knife, whereby contact of the knife therewith in a cutting operation will impart
- 10 to the knife a high speed of rotation.
6. The combination with a stationary housing, a shaft having a turret secured thereto, the shaft and turret fitted to rotate within parts of the housing, a stationary gear surrounding the shaft and secured to the housing, of two shafts journalled in the turret at right angles to each other, each having a transmission gear whereby the motion of one is imparted to the other, and one having a
- 15 gear engaging the teeth of the stationary gear, whereby it is rotated by reason of the rotation of the turret within the housing, a crank secured to one of the shafts, a freely rotatable circular cutter carried by said
- 20 crank, said crank adapted to project the cutter periodically into the path of a tube to be cut upon rotation of said shafts, whereby in a cutting operation rotation will be imparted to the cutter by its passage thorough the tube
- 25 to be cut.

7. In a cutting machine for tubes, the combination of a freely rotatable circular knife, means for revolving the knife bodily about an axis offset therefrom, and a rotary support for said means.

In testimony whereof I affix my signature.
JAMES B. PLATT.
